UNITED STATES PATENT OFFICE.

GEORGE E. WOOD, OF PLANTSVILLE, CONNECTICUT, ASSIGNOR TO STANLEY RULE AND LEVEL COMPANY, OF NEW BRITAIN, CONNECTICUT, A CORPORATION OF CONNECTICUT.

DESIGN FOR A TOOL-HANDLE.

No. 37,896.

Specification for Design.

Patented March 13, 1906.

Application filed July 29, 1905. Serial No. 271,859. Term of patent 14 years.

To all whom it may concern:

Be it known that I, GEORGE E. WOOD, a citizen of the United States, residing at Plantsville, Hartford county, Connecticut, have invented a new, original, and ornamental Design for a Tool-Handle, of which the following is a specification, reference being had to the accompanying drawings.

Figure 1 is a side elevation of a tool-handle,

showing my new design. Fig. 2 is a top plan view of same.

I claim—

The ornamental design for a tool-handle as shown.

GEORGE E. WOOD.
